RAYMOND S. MERRIETT, OF SYRACUSE, NEW YORK.

AUTOMATIC BRAKE-OPERATING MEANS FOR RAILWAY TRAINS.

Application filed August 11, 1923. Serial No. 656,848.

This invention relates to an automatic train controlling system in which the railway is divided into blocks of any suitable length and each block equipped with electrical apparatus adapted to cooperate with related apparatus on the engine, tender or other part of the train for automatically reducing the speed of or stopping a train when approaching dangerous conditions such for example, as another train or car in the preceding block, open bridges, sharp curves, switch yards, crossings and other permanent or temporary dangers which might require cautious approach.

The main object is to provide means whereby the approach of a train to any block in which any of the aforesaid dangers exist will automatically apply the brakes of that train to reduce its speed or stop the train before reaching the danger point.

Another object is to protect the various elements and translating devices against short circuits, leakages or deterioration by climatic conditions.

Other objects and uses relating to specific parts of the system will be brought out in the following description.

In the drawings:

Figure 1 is a diagrammatic view of a portion of a railway block system including certain apparatus connected therewith.

Figure 2 is a diagrammatic view of a portion of a track equipment and correlated part of the system carried by the engine, tender or other part of a train.

In Figure 1 is shown diagrammatically, a railway —1— divided into blocks as —A—, —B— and —C— along which the train indicated by a car axle —2— is movable, the rails of the several blocks being electrified from any suitable source of electric energy as batteries —3—.

Additional line conductors —4— extend along the railway and may be supplied with current from any suitable source of electric energy not shown.

Each block of the railway is equipped with a semaphore signal as —a—, —b—, —c— and —d—, and so on in the direction of travel of the train along the track, each signal being adapted to be operated by any of the well known automatic or manually operated mechanisms commonly used in block signals, but not necessary to herein illustrate or describe.

The axle —2— forms a part of the engine,

tender or other part of a train moving along the track —1— and equipped with the usual engineer's brake controlling valve —5— having an operating handle —6— shown in Figure 2 as in its extreme open position for releasing the brakes in a manner well known to those skilled in this art and therefore, unnecessary to herein illustrate or describe.

The present invention has to do more particularly with means controlled by the train moving along the track for automatically operating the brake controlling valve —5— through the medium of the lever —6— in case the driver should fail to see or heed the semaphore signal which may be set against him or should fail to reduce the speed of or stop the train in accordance with said signal, and involves the use of a cylinder —7— containing a reciprocating piston —8— which is adapted to be operated in one direction against the action of a retracting spring —9— by means of air or other fluid pressure through a suitable supply pipe —10— having a self-closing valve —11— for controlling the passage of air to said cylinder said valve being of the usual self-venting type to permit the return of the piston 8 when the valve 11 is closed.

The outer end of the piston rod is pivotally connected to one end of a link —12— having its other end slotted at —13— for receiving a pin —14— on the hand lever —6— of the brake valve —5—, said pin being normally engaged with the inner end of the slot when the valve lever —6— is thrown to its brake releasing position the length of said slot being substantially equal to the stroke of the piston —8—.

The slot —13— is of sufficient length to permit the hand lever —6— to be swung to its brake operating position without changing the normal position of the piston —8— thus permitting the engineer or driver to operate the brake valve —5— at will in the usual manner.

A pair of governors —15— and —15'— are mounted upon the engine and are geared or otherwise operatively connected to a pulley —16— which may be driven through the medium of a belt not shown connected to any suitable revolving part of said engine whereby the centrifugal throw of the weighted members of the governors will be directly proportionate to the speed of move-

ment of the train and will be transmitted to other movable parts as —17— and —17'— of the governors for making and breaking certain electric circuits of the automatic 5 brake controlling system hereinafter described.

Each block is provided with a plurality of, in this instance three, primary electromagnets —18—, —19— and —20— arranged 10 in sequence along the track in the direction of motion of the train, the magnets —18— and —19— being preferably located beneath opposite rails of the track while the magnets —20— are located in the road bed between the rails, as shown more clearly in 15 Figure 2.

As illustrated, the semaphore arms —a—, —b—, —c—, and —d— are pivoted to swing from a normal upright "clear" position as indicated at —a— and —d—, to a substantially horizontal "danger" position as indicated at 20 —c— or to an intermediate "caution" position as indicated at —b— to indicate to the engineer, the absence or presence of danger 25 in blocks ahead as they are approached by the train.

Associated with each semaphore is a self-closing reset switch —21— which is normally closed when the semaphore arm is in 30 its upright or "clear" position and also when it is in its "caution" position, but is adapted to be automatically opened by a member —22— on the semaphore when the latter is thrown to its danger position for a purpose 35 hereinafter described.

That is, each of the electric resetting switches —21— together with a normally open relay switch —23— and the corresponding reset magnet —20— of the corresponding 40 block are electrically connected in series across the main line circuit —4— by wires —24— and —25— so that when the relay switch —23— of any one of the blocks is closed, the reset magnet —20— of that block 45 will be energized.

The winding of each relay switch —23— is adapted to be connected across the battery circuit by the presence of a train in the corresponding block, one side of the adjacent battery being electrically connected by a 50 wire —26— to one of the rails while the other side of the same battery is connected to the winding of the corresponding relay and thence to the other rail whereby the presence 55 of an axle of the engine or any one of the cars of the train in that particular block will complete the battery circuit through that winding thereby closing the corresponding switch —23— to energize the adjacent reset magnet —20—.

Each semaphore is also provided with means, as a switch member —27— and cooperative pairs of terminals —28— and —29—, for connecting the primary electromagnets respectively across the circuit —4—

when the semaphore is shifted first to its "caution" position as shown at —b—, Figure 1 and then to its "danger" position as shown at —c—.

That is, one of each pair of terminals —28— is connected by wire —24— to one side of the circuit —4— while the other terminal of the same pair is connected by a wire —30— to one end of the winding of the electromagnet —18—, the other end of said winding being connected by a wire —31— to the opposite side of the circuit —4— preferably through the wire —25— so that when the semaphore is adjusted to its "caution" position to bring its contact member —27— into engagement with the terminals —28—, the electromagnet —18— which may be designated as the "caution magnet" will be energized.

In a similar manner, one of each pair of terminals —29— is connected by the wire —24— to one side of the circuit —4— while the other terminal of the same pair is connected by a wire —32— to one end of the winding of the electromagnet —19— which may be termed the "danger magnet," the other end of said winding being connected by a wire —33— to the other side of said circuit —4— preferably through the wire —25—.

As previously stated, each block of the railway is equipped with a set of the electromagnets —18—, —19— and —20—, the "caution magnet" being located under one rail near the beginning of the block while the "danger" magnet is located under the opposite rail beyond the center of the block and the "reset" magnet is preferably located in the road bed between the rails near the end of the block.

A corresponding number of secondary coils —18'—, —19'— and —20'— are mounted upon the engine or other part of the train in transversely spaced relation and adapted to travel in line with their cooperative magnets —18—, —19— and —20— and to be energized thereby as they pass over the same.

That is, the secondary coils —18'—, —19'— and —20'— are supported upon the engine or other part of the train in such manner as to travel in sufficiently close proximity to their respective magnets —18—, —19— and —20— to receive by induction current from said magnets for a purpose presently described, the coil —18'— being disposed directly over the rail under which the "caution" magnet —18— is placed, while the coil —19'— is placed directly over the rail under which the magnet —19— is installed and the coil —20'— is placed directly over the center line of the road bed between the rails so as to pass directly over the "reset" magnets —20— as the train moves along the track.

The opposite ends of the winding of the coil —18'— are connected by wires —34— to

opposite ends of a solenoid winding —35— while the opposite ends of the winding of the coil —19— are similarly connected by wires —34— to opposite ends of a similar solenoid winding —35'—, and the opposite ends of the coil —20— are connected by wires —36— and —36'— to additional solenoid windings —37— and —37'—.

The solenoid windings —35— and —37— 10 constitute parts of a solenoid switch —38— while the windings —35'— and —37'— constitute parts of a similar solenoid switch —38'— said switches being of a type which, once closed, remain closed until again opened 15 by the energizing of the coils —37— and —37'— respectively.

These solenoid switches —38— and —38'— 20 are mounted upon the engine or other part of the train, the windings —37— and —37'— being on similar ends of the corresponding switches for opening or resetting the same when the secondary coil —20'— passes over one or more of the underlying energizing electromagnets —20—.

25 On the other hand, the windings —35— and —35'— are mounted upon the opposite ends of the movable switch members for closing the latter when energized by the passing of the corresponding secondary coils —18'— and —19'— over their underlying energized electromagnets —18— and —19—.

One of the terminals of each of the solenoid switches —38— and —38'— is connected by a wire —39— to a reversing switch —40— which in turn is electrically connected by wires —41— to the movable members of a pair of governor operated switches —42— and —42'—.

40 The other terminals of the solenoid switches —38— and —38'— are electrically connected by wires —43— to one end of a solenoid winding —44— which surrounds the stem of the valve —11—, Figure 2, and has its other end connected by a wire —45— to one side of an electric switch —46—, the other side of said switch being connected by a wire —47— to one side of a dynamo —48— which is also mounted upon the engine or other part of the train and adapted 45 to be operated by a moving part thereof, the other side of the dynamo being connected by wires —49— to the governor operated switches —42— and —42'—.

50 The movable members of the switches —42— and —42'— are mounted upon the axially movable members —17— and —17'—, respectively, of the governors —15— and —15'— and are normally open when the train is at rest or moving below a predetermined speed, but one of the governors, as for example, the right hand one, Figure 2, is adapted to close its switch at a relatively slow speed of say nine miles per hour, more or less, while the other governor as —15—, 55 is adjusted to close its switch —42— at a

relatively higher speed of say forty miles per hour of the train, it being understood that the first named governor will remain closed during all the intervening speeds.

An electric switch —50— is connected in 70 one side of the dynamo circuit, Figure 2, between the switch —46— and the solenoid winding —44— and has its movable member mounted on the engineer's brake valve operating member —6— to normally close 75 the switch —50— when the brake operating lever —6— is adjusted to release the brakes, but is adapted to be opened when the lever is thrown to its extreme brake applying 80 position.

Assuming that the track is clear, and that the semaphores are accordingly set in their clear positions as indicated at —a— and —d— and that a train is moving along the track at normal speed and that the engineer's brake valve lever —6— is in its open position, then as the train passes through the successive blocks, one or more of the axles as —2— will close the circuits through the several relay windings of the switches 90 —23— to close said switches and thereby to energize the corresponding reset magnets —20— so that as the secondary coil —20'— on the train passes over the electromagnets —20—, the corresponding secondary circuits 95 —36— and —36'— including the solenoid windings —37— and —37'— will be energized to assure the opening or resetting of the switches —38— and —38'— thus preventing the energizing of the solenoid coil 100 —44— and leaving the valve —11— closed and the engineer's brake valve in release position.

Now, assuming that the train is in one of the blocks as —C— and that it is being 105 followed by another train in which case the semaphore as —c— of that block is set to its danger position as shown, and that the semaphore of the next preceding block B has been set to its "caution" position, then the 110 members —22— and —27— of the "danger" signal as —c— will have been set to open the switch —21— and to close the switch —29— thereby closing the branch circuit through the wires —24— and —25— and "danger" magnet —19— of the next preceding block B while the members —22— and —27— of the "caution" signal b in the last 115 named block as —B—, will be set to allow the switch —21— to close and to also close the adjacent switch —28—, leaving the corresponding switch —29— open, thereby closing the branch circuit of the succeeding block B through the corresponding wires —24— and —25— and "caution" magnet —18— of that block B.

Under these conditions, the following train entering the next preceding block as —B— will first bring the secondary coil 120 —18'— over the "caution" magnet —18— 125

thereby energizing the solenoid winding —35— to effect the closing of the corresponding switch —38— and simultaneously energizing the solenoid winding —44— to open the valve —11— and thus cause the operation of the piston —8— and link —12— to throw the engineer's brake valve handle —6— to its braking position and also to engage and close the normally open switch —46— at which time the switch —50— will have been opened, it being understood that the governor switch —42— will then be closed by the speed of the train if above nine miles per hour and that the reversing switch 40 will also be closed to complete the dynamo circuit through the wires —39— and —41—.

This operation of the piston —8— by air pressure through the open valve —11— will cause the operation of the engineer's brake valve to apply the brakes and thereby to automatically slow down the train to "caution" speed.

Now as the following train proceeds under "caution" speed, through its block, as —B—, the passing of the danger coil as —19— over the then energized danger magnet —19— will cause the energizing of the solenoid coil —35— through the wires —34— thereby closing the electric switch —38— of the corresponding dynamo circuit —39— and —41— at which time the governor switch —42— and reversing switch 40 will have been closed to complete the circuit.

As previously stated, the presence of a train in any one of the blocks will close the battery circuit through the relay switch —23— of that block for energizing the corresponding electromagnet 20 when the block in advance is under "clear" or "caution" conditions, its secondary coil —20— and solenoids —37— and —37'— will be energized to open the corresponding switches —38— and —38'— thereby de-energizing the solenoid coil —44— to permit the return of the piston —8— and link —12— and consequently opening of the switch —46— whereupon the engineer's brake valve lever —6— may be operated in the usual manner independently of the link —12— but will be held against movement to its brake applying position by said link and piston as long as the valve —11— remains open.

Now, if the train proceeds under a speed lower than caution speed the governor —15— will be correspondingly extended axially to open the switch —42—, thereby breaking the circuit through the solenoid —44— and allowing the valve —11— to close and also permitting the spring —9— to return the piston —7— and ring —12—, leaving the brake controlling lever —6— in its braking position but free to be moved to its brake releasing position.

Then, if the engineer should operate the lever —6— to release the brake and increase the speed of the train above the safe limit, of, in this instance, forty miles per hour, the brakes will again be automatically applied 70 and this cycle of operation will continue until there has been a definite reset from the track apparatus.

I have thus far described the automatic operation of the brake applying lever to its 75 braking position by the setting of the semaphores of the several blocks to their "clear", "danger" and "caution" positions, by any suitable means either automatic or at will, but another not less important feature of the 80 invention consists in providing means controlled by the moving of the train through the several blocks for effecting the operation of the brake controlling lever to its braking 85 position, independently of the semaphores and is particularly useful in case the semaphores should fail to operate or be wrongly set while trains are passing through the blocks.

For this purpose, each block is equipped 90 with a plurality of, in this instance, three, relay switches —51—, —52— and —53—, the switches —51— being preferably of the normally closed self-closing type, while the switches 52 and 53 are of the normally open 95 self-opening type.

The windings of the relay switches —51— and —53— of each block are respectively connected by wires —54— and —55— across the battery circuit of that block 100 through the medium of branch circuits —56— each having one side thereof connected to one of the rail sections and its other side connected to one pole of the local battery which has its other pole connected to the 105 opposite rail section so that the presence of a train in that block will close the local circuits through the windings of the relay switches —51— and —53—, and thereby 110 open the switch —51— to break the circuit through the relay switch —23— and "reset" magnet —20— of the next preceding block and at the same time to close the switch —53— for energizing the "danger" magnet —19— of the same preceding block. 115

The winding of the relay switch —52— of each block is connected by wires —57— across the battery circuit —56— of the next succeeding block so that a train in any block 120 will close the circuit through said winding and thereby close said switch to energize the "caution" magnet as —18— of the next preceding block.

For example, assuming now that a train 125 is moving along the track in block —C—, then the axle as —2— of a part of the train will electrically connect the opposite rails and thereby close the battery circuit through the winding of the relay switch —23— of that block to close said relay switch at which 130

time the relay switch —51— of block —D— will be in its normal closed position thereby connecting the reset magnet —20— of station —C— across the circuit —4— for energizing said reset magnet.

At the same time, the presence of the axle —2— in block —C— will close the battery circuit through the winding of the relay switch —51— in block —C— thereby opening said switch and breaking the circuit through the relay switch —23— of the next preceding block —B— to de-energize the corresponding relay magnet —20—.

Simultaneously with the opening of the switch —51— of block —C—, the relay switch —53— of the same block will be energized and closed for energizing the "danger" magnet —19— in block —B— and at the same time, the relay switch —52— of block —B— will be energized and closed to energize the "caution" magnet —18— of block —B—.

When any one of the semaphores is set at "caution," as at —b—, its switch member —27— will close the contacts —28— and thereby close the circuit from the line 4 through the caution magnet of the corresponding block, as —B—, irrespective of the companion switch —52—, but if the semaphore, as —b—, should not be set at "caution" the switch —52— will be closed by a train in the block ahead to cause the energizing of the caution magnet in block —B—.

Now, if a train following that in block —C— enters block —B— at full or normal speed, the governor switches —42— and —42'— will be closed and the reversing switch —40— will have been adjusted to connect the wires —39— and —41— for connecting the switch —42— to the corresponding switch —38— and switch —42'— to the switch —38'— under which conditions, it is assumed that the engineer's brake valve —6— is in its brake releasing position, and that the valve —11— is closed, and the piston —8— and link —12— in their normal innermost positions to which they are forced by the spring —9—, the switch —50— being then closed.

Then as the train enters block —B—, and the secondary coil —18'— passes over the energized "caution" magnet —18— of that block, the secondary circuit —34— leading from the coil —18'— together with the solenoid —35— will be energized by induction to close the switch —38—.

This closing of the switch —38— will connect the solenoid winding —44— of the valve —11— in the dynamo circuit through the closed switches —40—, —42— and —50— thereby opening the valve —11— and allowing the air pressure in the pipe —10— to force the piston —8— outwardly against the action of its retracting spring —9—, thereby forcing the engineer's brake lever —6—

to its braking position through the medium of the link —12—, which at the same time, engages and closes the switch —46— and opens the switch —50—.

The application of the brakes in the manner just described will of course, cause the slowing down of the train immediately upon the passage of the secondary coil —18'— over the "caution" magnet —18— in block —B—, but the brake lever will be held in its brake applying position until the speed is reduced sufficiently to open the switch —42'— as previously explained.

As the train continues to move along block —B— and the secondary coil —18'— passes its energizing magnet —18—, it will become de-energized, thereby de-energizing the solenoid winding —35—, but permitting the switch —38— to remain closed for energizing the solenoid coil —44— and thereby keeping the valve —11— open and the piston —8— and link in position to close the switch —46— until the continued movement of the train along block —B— causes the secondary coil —19'— to pass over the "danger" magnet —19— in the same block at which time, and only when the speed is above nine miles per hour, the solenoid coil —35'— will be energized to close the switch —38'— thereby continuing the energizing of the coil —44—.

As the following train continues to advance slowly, under "danger" by the application of the brakes in block —B— as just described, the secondary reset coil —20'— will pass over its companion reset magnet —20— thereby energizing the reset coils —37— and —37'— to open the switches —38— and —38'— in case they are closed, and energizing both of the coils —35— and —35'— and also the coil —44— to allow the valve —11— to close which, in turn, permits the return of the piston —8— and link —12— by the spring —9— and incidentally opens the switch —46—.

This automatic movement of the brake lever —6— to its brake applying position, first by the passage of the secondary "caution" coil —18'— over its companion "caution" magnet —18— and then the subsequent passing of the secondary danger coil —19'— over its companion magnet —19—, causes the train to move very slowly, if at all, or under full control from block —B— into block —C— thereby reducing to a minimum the liability of rear end collision with the train in block —C—.

In like manner, the movement of a train in any block causes the automatic application of the brakes of any succeeding train entering the next preceding block, and although I have shown and described this automatic means for applying the engineer's brake valve in connection with semaphore operated means for effecting the same result

in applying the brakes, I do not wish to limit myself to the use of semaphores nor to the detail construction of various other parts of the system as herein described.

5 I claim:

1. In an automatic brake-operating system for railways, the combination with a railway divided into "blocks", of an electro-magnet in each "block" directly under one rail only of the track, means in one "block" for energizing an electro-magnet of another "block", a brake-controlling member carried by a train or car movable along the track, inductive means carried by the car or train

10 15 directly over the rail under which the electromagnets are placed and movable through the fields of the electro-magnets for receiving current therefrom by induction, and means actuated by the energizing of the inductive means for causing the operation of said member to apply the brakes.

2. An automatic brake-operating system for railways as in claim 1, in which each block includes a signal movable to different 20 25 positions, and an electric switch of its block operated by the signal to close the circuit through the magnet in another "block" when the signal is in one position and for breaking said circuit when the signal is in another position.

3. In an automatic brake-operating system for railways, the combination with a railway divided into "blocks", of an electro-magnet in each "block" directly under one rail only of the track, means in one "block" for energizing an electro-magnet of another "block", a brake-controlling member carried by a train or car movable along the track, inductive means carried by the car or train 30 35 directly over the rail under which the electro-magnets are placed and movable through the field of the electro-magnets for receiving current therefrom by induction, and means including an electro-magnetic switch actuated by the energizing of the inductive means for causing the operation of said member to apply the brakes.

4. An automatic brake-operating system for railways as in claim 3 in which each 50 "block" is equipped with an additional electro-magnet directly under the other rail of the track, means actuated by the presence of a car or train in one "block" for energizing the additional electro-magnet in the preceding block, additional inductive means carried by the train directly over said rail and movable through the fields of the additional electro-magnets for receiving current therefrom, and means actuated by the energizing of the additional inductive means for opening said switch.

5. In an automatic brake-operating system for railways, the combination with a railway divided into "blocks", of an electro-magnet in each "block" directly under one

only of the rails of the track, electrically operated means actuated by the presence of a car or train in one "block" for energizing the electro-magnet in the next preceding "block", a secondary electric circuit on the train having inductive means directly over said one of the rails movable through the fields of said electro-magnets for receiving current therefrom by induction, a brake controlling member on the car or train, and means actuated by the energizing of the secondary circuit for causing the operation of said brake controlling member to apply the brakes.

6. An automatic brake-operating system for railways, as in claim 5, in which the last named means includes a normally open electric switch, and means actuated by the movement of the car or train along the track for closing said switch when the train reaches a pre-determined speed.

7. An automatic brake-operating system, as in claim 5, in which the last named means includes an electro-magnetically operated valve and an electro-magnetically operated switch in circuit with the winding of the electro-magnetically operated valve and having its winding in the secondary induction circuit.

8. In an automatic brake-operating system for railways, the combination with a railway divided into "blocks", of an electro-magnet in each "block" directly under one rail only of the track, electro-magnetic switches, one for each block and each in circuit with the electro-magnet of the next preceding "block" and having its winding forming a part of a local circuit connected to both track-rails of its corresponding "block" whereby a car or train present in one "block" will cause said circuit to close the switch and energize the electro-magnet in the next preceding "block", a brake-controlling member on the car or train, a secondary circuit on the car or train having an induction device directly over said rail and movable through the fields of the electro-magnets for receiving current therefrom, and means actuated by the energizing of the inductive device in the secondary circuit for causing the operation of the brake-controlling member to apply the brakes.

9. In an automatic brake-operating system for railways, the combination with a railway divided into "blocks", each "block" being equipped with a plurality of electro-magnets in spaced relation along the track and termed respectively a "danger" magnet and a "resetting" magnet, normally open relay switches, one for each "block" and each in circuit with the "reset" magnet of the corresponding "block" and having its winding connected to the rails of that "block", whereby the presence of a car or train in one "block" closes the circuit through the wind-

ing and thereby closes its switch to energize the "reset" magnet, additional normally open relay switches, one for each "block" and each in circuit with the "danger" magnet of the next preceding "block" and having its winding connected to the rails of the corresponding "block" whereby the presence of a car or train in one "block" will close the corresponding switch, and thereby energize the "danger" magnet in said preceding "block", a brake-controlling member on the car or train, induction devices carried by the train and movable respectively through the fields of the "danger" magnet and "reset" magnet for receiving current therefrom, means including an electric switch, actuated by the energizing of the induction device for the "danger" magnet for causing the operation of the brake-controlling member to apply the brakes, and additional means actuated by the energizing of the induction device for the "reset" magnet for opening said switch.

10. In an automatic brake-operating system for railways, the combination with a railway divided into "blocks", an electro-magnet in each "block" designated as a "caution" magnet, another electro-magnet in each "block" designated as a "danger" magnet, the magnets of each block being arranged in spaced relation along the rails of that "block", a relay "caution" switch in each "block" in circuit with the "caution" magnet of that "block" but having its winding connected to the rails of the next succeeding "block", a relay "danger" switch in circuit with the "danger" magnet of the next preceding "block", and having its winding connected to the rails of the next succeeding "block", a brake-controlling member on the train, a secondary "caution" circuit and a secondary "danger" circuit both mounted on the car or train, said "caution" circuit including therein an induction device movable through the fields of the "caution" magnets to be energized thereby, the induction "danger" device being movable through the fields of the "danger" magnet to be energized thereby, and means actuated by the energizing of either of said devices for causing the operation of the brake-controlling member to apply the brakes.

11. In an automatic brake-operating system for railways, the combination of a railway divided into "blocks", each "block" being equipped with a "caution" magnet under one rail and a "danger" magnet under the opposite rail, and a "reset" magnet between the rails, normally open relay switches, one

for each "block" and each in circuit with the "reset" magnet of the corresponding "block" and having its winding connected to the opposite rails of that "block" whereby the presence of a car or train in each "block" will close the relay switch of that "block", normally closed electro-magnetic switches, one for each "block" and each in circuit with the relay switch of the next preceding "block" and having its winding connected to the rails of its corresponding "block" whereby the presence of a car or train in that "block" will open its electromagnet switch, and thereby break the circuit through the "reset" magnet of said next preceding "block", relay "caution" switches one for each "block" and each in circuit with the "caution" magnet of its "block" but having its winding connected to the rails of the next succeeding "block" whereby the presence of a car or train in that "block" will energize the "caution" magnet in the next preceding "block", relay "danger" switches, one for each "block" and each connected in circuit with the "danger" magnet of the next preceding "block", but having its winding connected across the rails of its corresponding "block", whereby the presence of a car or train in the one "block" will energize the "danger" magnet of said preceding "block", a brake-controlling member on the car or train, air operated means for operating said member to apply the brakes, a normally closed valve controlling the supply of air to said air operated means, electrically operated means for opening the valve, a normally open electric switch for controlling the last named means, an induction device carried by the car or train and movable through the fields of the "caution" magnets for receiving current therefrom, means actuated by the energizing of said device for closing the last-named switch, another induction device carried by the car or train and movable through the fields of the "danger" magnets for receiving current therefrom, means actuated by the energizing of the last named device for closing the circuit through the valve operating means, an additional induction device carried by the car or train and movable through the fields of the "reset" magnets for receiving current therefrom, and means actuated by the energizing of the last-named device for opening the last named switches.

In witness whereof I have hereunto set my hand this 2nd day of August, 1923.

RAYMOND S. MERRIETT.
